(57) **CLAIM**

The ornamental design for a pillow, as shown and described.

DESCRIPTION

FIG. 1 is a perspective view of a pillow showing my new design;

FIG. 2 is a front view thereof;

FIG. 3 is a rear view thereof;

FIG. 4 is a left side elevational view thereof;

FIG. 5 is a right side elevational view thereof.

FIG. 6 is a top view thereof;

FIG. 7 is a bottom view thereof; and,

FIG. 8 is a partial enlarged view of the portion circled in FIG. 1.

The broken lines indicating an enlargement portion of the design form no part of the claimed design.
